UNITED STATES PATENT OFFICE.

JOSEPH ELWELL COLE, OF DACRE, ONTARIO, CANADA.

RURAL MAIL BOX.

Application filed March 12, 1923. Serial No. 624,640.

To all whom it may concern:

Be it known that I, JOSEPH ELWELL COLE, a citizen of the United States of America, and resident of Sunset Mine, town of Dacre, 5 in the Province of Ontario and Dominion of Canada, have invented certain new and useful Improvements in Rural Mail Boxes, of which the following is a specification.

This invention relates to improvements in 10 rural mail boxes and the objects of the invention are to provide a simple, effective and weather-proof mail box for rural delivery of mail, which can be economically made and in which the various parts are particularly designed to perform satisfactorily the 15 several functions required of them.

Further objects are to provide a box of this character that will not readily get out of order or be displaced while in use, that 20 can be quickly opened and closed by the mail carrier to deliver the mail thereto and withdraw it therefrom.

Still further objects are to provide in a 25 box of this character signalling means by which a signal may be given to the owner of the box or to the carrier, indicating whether or not there is mail in the box.

With the foregoing and other objects in view, the invention consists essentially in 30 the improved construction and arrangement of parts hereinafter described in detail in the present specification and illustrated by the accompanying drawings.

Referring now to the drawings, in which 35 like characters of reference indicate corresponding parts in each figure,

Figure 1 is a perspective view of an embodiment of the invention.

Figure 2 is a longitudinal sectional elevation.

Figure 3 is an elevation of the inner end.

Figure 4 is a cross sectional view.

Figure 5 is a sectional detail on the line 5—5 of Figure 1.

Figure 6 is a sectional detail of the improved box bearing supporting the bottom roller.

Figure 7 is a perspective view of the signalling member.

Figure 8 is a perspective view of the supporting roller.

In the drawings, A designates the casing or mail box member designed to contain the mail matter and adapted to be supported at a convenient height from the ground by any suitable form of support. In the pres-

ent example of the invention, it is illustrated as being supported by a single supporting standard 10 to which the casing is suitably secured.

The mail box or casing A is preferably 60 rectangular, both in cross section and longitudinal section, and is constructed of any suitable or convenient material with a view to providing durability and longevity in 65 satisfactory and efficient use. 11 is the forward end of the casing adapted to be opened. Within the casing is mounted a carriage member C and designed to carry the mail matter, this carriage being mounted with 70 freedom to reciprocally slide backwardly and forwardly on a suitable guideway.

As here shown, the carriage is in the form 75 of rectangular box mounted at the bottom on guideways 12 and extending substantially the full length of the casing to be operated backwardly and forwardly by means of a pivotally mounted pull or handle member 13 fixedly secured through a bracket member 14 in the front end of the carriage and 80 adapted to be readily grasped by the operator.

To facilitate movement of the carriage, a 85 roller 15 is mounted transversely in the casing and adapted to engage and support the underside of the carriage C. This roller is provided with improved box bearing 16.

To return the carriage to normal position, suitable means are provided and, as here 90 shown, comprise a weight 17 connected to a cord 18 which extends over the roller 15 and is connected to the forward end of the carriage. In this way, when the carrier, by means of the handle 13, pulls out the carriage it will automatically, on being released 95 by the carrier, be drawn to its innermost position and remain in such position.

The front of the carriage is adapted to be normally closed by a door D designed to automatically open upwardly as the carriage 100 is pulled forward. To effect this, the door is hinged at 19 and is designed to be engaged by rollers 20 mounted on a cross rod 21 suitably journaled and carried by the member 22 of the carriage.

It will be seen as the carriage is 105 pulled forwardly the door will be swung upwardly, as indicated in dotted lines Figure 2, forward movement of the carriage being limited by engagement with suitable stop 110 means 23.

Signalling means are associated with the

carriage and, as here shown, comprise a longitudinally extending rod 24 suitably journaled in the roof 25 of the casing and formed with a semaphore or other suitable signalling device 26 which may, if desired, have a lamp at its rearmost end, the semaphore or signal being adapted to be set in a plurality of different positions and to be securely held in these positions against the 10 action of the wind by means of a squared portion 27 adjacent the operating handle 28 and designed in position to lock the signalling member as required in combination with the cross member 29 of the roof. In 15 this way, the signal may be locked or set with the semaphore extending laterally or with the semaphore extending upwardly, the upward position indicating, for instance, that there is mail in the box for delivery 20 and the side position indicating that there is mail to be collected. The inner end of the rod is suitably journaled in the roof 25 at 30.

In operation the rod has sufficient freedom of longitudinal movement to enable the squared portion to be withdrawn from the recess in the cross member 29.

A further and essential improvement in my letter box consists in mounting the 30 name of the owner on the box and this, as here shown, is accomplished by means of a weather-proof frame 31 on the box which is adapted to slidably engage with a casing of weather-proof and transparent material in 35 which is mounted a card having the owner's name printed or stamped thereon. The transparent material may be of glass or any other suitable transparent medium as long as it is water-proof and is slid into this 40 frame and fastened into place by any suitable means.

32 indicates a coin box which may be conveniently located beneath the roof at the forward end, having a sliding door 33 in the 45 bottom which may be readily opened by the postman to permit the coins to drop into his hand.

As many changes could be made in the above construction and many apparently 50 widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. A mail box of the character described comprising a casing closed at one end and 60 open at the other end, a reciprocal carriage in the casing, a door adapted to automatically open and close as the carriage is moved forwardly and rearwardly, said door being hingedly mounted on the casing and a roller 65 on the carriage adapted to engage the door.

2. A mail box of the character described comprising a casing, a reciprocal carriage in the casing, a door adapted to automatically open and close as the carriage is moved forwardly and rearwardly, a weight, a cord extending from the weight to the carriage, a roller engaging the cord, and also forming a support for the bottom of the carriage. 70

3. A mail box of the character described comprising a casing, a reciprocal carriage in 75 the casing, a door adapted to automatically open and close as the carriage is moved forwardly and rearwardly, and a semaphore signalling device including a rod, a block on the rod, a cross-member having a recess to 80 receive the block and designed to hold it in a plurality of adjusted positions, and means on the outside of the casing designed to slidably engage with water-proof means carrying a card bearing the owner's name. 85

4. A rural mail box comprising, in combination, a base, a casing on the base having an open end and having openings formed on opposite sides leading from the open end and a guideway at the bottom of the casing, 90 a carriage mounted on the guideway and reciprocal within the casing, a hinged door on the casing normally closing the front of the carriage, a roller on the carriage engaging the underside of the door and adapted to return the same after the carriage is moved forwardly, an operating rod connected to the crank by which it may be moved forwardly, and gravity means for returning the carriage to its innermost position, and means 100 on the casing adapted to engage with and retain card-carrying water-proof means indicating the owner's name.

5. A rural mail box comprising, in combination, a base, a casing on the base having 105 an open end and having openings formed on opposite sides leading from the open end and a guideway at the bottom of the casing, a carriage mounted on the guideway and reciprocal within the casing, a hinged door 110 on the casing normally closing the front of the carriage, a roller on the carriage engaging the underside of the door and adapted to return the same after the carriage is moved forwardly, an operating rod connected to the crank by which it may be moved forwardly, gravity means for returning the carriage to its innermost position, a longitudinally extending signalling rod, signalling means on the rod, and means for holding 115 the signalling rod in adjusted position, and means on the outside of the casing for carrying water-proof indicating means for the casing. 120

In witness whereof I have hereunto set 125 my hand in the presence of a witness.

JOSEPH ELWELL COLE.

Witness:

W. T. CUFFE QUIN.
